UNITED STATES PATENT OFFICE.

WILLIAM T. HARPER, OF FLAGSTAFF, ARIZONA TERRITORY.

NON-REFILLABLE BOTTLE.

No. 861,589.

Specification of Letters Patent.

Patented July 30, 1907.

Application filed August 21, 1906. Serial No. 331,502.

To all whom it may concern:

Be it known that I, WILLIAM T. HARPER, a citizen of the United States, residing at Flagstaff, in the county of Coconino, Territory of Arizona, have invented certain new and useful Improvements in Non-Refillable Bottles, of which the following is a specification.

The present invention relates to means for the prevention of fraud in bottled goods by the substitution of spurious or inferior goods for the original contents of the bottle.

The object of the invention is to provide a simple and inexpensive device which can be readily applied to the bottle and which will operate to prevent any refilling thereof.

For a full understanding of the invention and the merits thereof and also to acquire a knowledge of the details of construction of the means for effecting the result, reference is to be had to the following description and accompanying drawings in which:

Figure 1 is a vertical sectional view through a bottle constructed in accordance with the invention; and, Fig. 2 is a top plan view of the neck of the bottle.

Corresponding and like parts are referred to in the following description and indicated in all the views of the drawings by the same reference characters.

The numeral 1 designates the bottle which may be of any suitable type, and 2 the neck thereof which is pressed inwardly or contracted at 3 to form a seat for the valve 4. The portion of the neck 2 above the valve seat 3 preferably flares outwardly as shown in the drawings. The valve 4 which normally rests upon the valve seat 3 is in the nature of a ball and may be formed of any suitable material such as rubber, cement or glass. A tube 5 fits within the bottle neck and is secured in position above the ball 4. This tube 5 may be formed of any suitable material such as cork and is capped by the perforated disk 6 which fits against the upper face of the same and is formed of spring metal so as to engage with the diverging sides of the bottle neck when pressed downwardly. A valve 7 operates to normally close the opening through the disk 6 and prevent any liquid from entering the bottle 1. A valve stem 8 is connected to the valve 7 and extends downwardly through the openings in the disk 6 and tube 5 to form a guide for the valve and limit the movement of the same. This latter result is accomplished in the present instance by flaring the lower end of the stem 8 downwardly so as to engage with the perforation through the

disk 6 when the valve reaches the limit of its upward movement.

The mouth of the bottle is formed with the outwardly projecting annular rib 9 around which a metallic ring 10 is fastened. The outer edge of this ring 10 is bent inwardly so as to bear against the interior portion of the neck of the bottle and form a seat for the reception of the cork which is removable in the usual manner and forms a closure for the bottle to prevent evaporation of the contents. In order to provide for the ready removal of the cork 11, a band 12 of wire or similar material is provided which extends around the cork and has a finger piece 13 formed in connection therewith. When formed of wire, as in the present instance the finger piece 13 is made integral with the band and the wire can be embedded in cuts in the sides of the cork. In the operation of the device it will be apparent that when the bottle is inverted, the valves 4 and 7 will fall away from their seats and permit the contents of the bottle to flow outwardly. However, when the bottle is in its normal or upright position the valves 4 and 7 rest upon their seats and form a tight closure which effectively prevents the forcing of any liquid within the bottle.

Having thus described the invention, what is claimed as new is:

1. The combination of a bottle having the neck portion thereof contracted, a valve normally resting upon the contracted portion of the neck to prevent the entrance of any liquid within the bottle, a tube fitting in the neck of the bottle beyond the valve, a perforated disk fitting against the tube, a valve normally closing the opening through the perforated disk, and a valve stem carried by the valve and extending through the opening in the disk, the end portion of the stem being enlarged so as to engage the disk and limit the movement of the valve.

2. The combination of a bottle having the neck thereof contracted, a valve normally resting upon the contracted portion of the neck, a tube fitting within the neck of the bottle beyond the valve, a perforated disk fitting against the tube, a valve fitted upon the perforated disk and cooperating with the before mentioned valve to prevent any liquid from being forced in the bottle, and a valve stem secured to the second mentioned valve and passing through and adapted to engage the perforated disk to limit the movement of the valve.

In testimony whereof I affix my signature in presence of two witnesses.

WILLIAM T. HARPER. [L. S.]
